UNITED STATES PATENT OFFICE.

HERMAN E. KRUECKE, OF MILWAUKEE, WISCONSIN.

HYDRAULIC AIR-PUMP.

1,117,581.

Specification of Letters Patent. Patented Nov. 17, 1914.

Application filed January 13, 1913. Serial No. 741,620.

To all whom it may concern:

Be it known that I, HERMAN E. KRUECKE, a citizen of the United States, and resident of Milwaukee, in the county of Milwaukee and State of Wisconsin, have invented new and useful Improvements in Hydraulic Air-Pumps, of which the following is a description, reference being had to the accompanying drawings, which are a part of this specification.

This invention has for its object to provide an air pump operated by water pressure, such as the pressure within the water main of a city water supply system.

The invention consists in the air pump as herein claimed and all equivalents.

Referring to the accompanying drawings in which like characters of reference indicate the same parts in different views, Figure 1 is a central sectional elevation of an air pump constructed in accordance with this invention, the plunger being in its lower position; Fig. 2 is a similar view with the plunger in its upper position; Fig. 3 is a sectional view of the pump in the position shown in Fig. 2, the sectional plane being at right angles to the sectional plane of Fig. 2; Fig. 4 is a transverse sectional view on the plane of line 4—4 of Fig. 1.

In these drawings 10 indicates an air cylinder which has a heavy metal plunger 11 fitting therein and which is equipped with an inlet check valve 12 and an outlet check valve 13 at its upper end through which air is drawn and expelled as the result of vertical reciprocations of the plunger in the well known manner.

The plunger at its lower end is provided with a lip ring 14 held in place by a flanged nut 15 threaded on the reduced end of the plunger and this lip ring of leather or other desirable material maintains a tight fit between the plunger and the walls of the cylinder 10. At the center of the plunger there is an opening which is closed at its upper end by a screw plug 16 and which is provided at its lower end with a shoulder 17 and within this opening there are two or more telescoping tubes 18 with inturned shoulders at their lower ends and outwardly turned shoulders at their upper ends, the shoulder at the upper end of the outer tube engaging with the shoulder 17 of the plun-

ger and the shoulder at the upper end of the inner tube engaging with the inturned shoulder at the lower end of the outer tube when the plunger is in its upper position as shown in Fig. 2. A leaded valve stem 19 is contained within the inner tube 18 and in said position of the parts the head at its upper end engages the inturned shoulder at the lower end of the inner tube as shown in Fig. 2. This valve stem 19 carries a number of valve rings 20 suitably spaced apart and slidably fitting within a valve casing 21 which is fixed in place within a plug 22 at the lower end of the cylinder and the movements of the valve rings within the valve casing serve to change the supply in the exhaust connections of a valve plunger 25 which controls the supply in the exhaust connections to the lower end of the cylinder. A flanged nut 23 threaded on the upper reduced end of plug 22 is engaged by a disk 24 carried by the valve stem 19 to limit the upward movement of the valve stem and the parts connected with it.

The plug 22 forms a part of a cylindrical casing or base casting for the pump structure and this casing which is on a horizontal axis has a valve plunger 25 fitting therein with a valve 26 carried on the end of its short stem 27 and fitting within a valve opening 28 of the casing of smaller diameter than the cylindrical portion and adapted to move from said valve opening to a corresponding opening in a water discharge plug 29 threaded in the end of the casing and having suitable connection 30 with a water discharge pipe. There is an annular space 31 between the valve opening 28 and the water discharge plug 29 which communicates with the interior of the air cylinder through a pair of openings 32 through the casing and this space is alternately in connection with the interior of the water discharge plug 29 when the valve 26 is in the position shown in Fig. 2 and with the water supply when the valve is in the position shown in Fig. 1, said water supply consisting of a pipe connection 33 at the side of the casing between the plunger 25 and the valve 26. Thus in one position of the valve, as shown in Fig. 1, water from the pressure supply is admitted to the lower end of the air cylinder, passing from the

water supply connection 33 through the plunger chamber and the valve opening 28 and through the annular space 31 and openings 32 and this pressure serves to lift the 5 plunger 11, which is preferably of solid metal to give it the desired weight and the lifting movement of the plunger compresses the air above it in the cylinder and forces it out through valve 13. In the other position 10 of the valve, as shown in Fig. 2, communication between the air cylinder and the water supply is closed by said valve fitting in its opening 28 and the air cylinder is in communication with the water discharge 15 plug 29 so that the water within the air cylinder may escape therefrom, returning through the openings 32 and the space 31 to the interior of the water discharge plug 29, thus allowing the plunger 11 to descend 20 which it does promptly because of its weight, in the meantime drawing in a new charge of air to the upper part of the air cylinder through valve 12.

The change in position of the valve 26 is 25 automatic and controlled by the position of the plunger. The cylinder of the casing is closed by means of a screw cap 34 and the space between it and the plunger 25 is the communication through a passageway 35 30 with an annular groove in the valve casing 21 having a series of radial openings leading from it to the interior of the valve casing. There are similar grooves with their 35 radial openings in the valve casing above and below the one mentioned, the one above having communication through a passageway 36, shown in Fig. 3, to the interior of the plunger chamber where it receives the pressure of the water in the pressure supply 40 and the one below having communication through a passageway 37 and a bent tube 38 with the interior of the water discharge plug 29, as shown in Figs. 1 and 2. When the valve rings 20 are in position for establishing 45 communication between passageway 35 and passageway 36, which position is the one shown in Fig. 1, communication is established from the water pressure supply direct to the end of the plunger chamber so that 50 both sides of the plunger 25 are subjected to the same pressure, but the valve 26 which has this pressure of the water mains on one side thereof has no pressure opposing it and consequently it is moved to and held in the 55 position shown in Fig. 1 to establish connection from the water supply to the lower end of the air cylinder to cause the plunger 11 to rise and compress the air above it. When the plunger reaches the upper end of its 60 movement the valve stem 19 is lifted thereby and the changed position of the valve rings thereof serves to interrupt the connection between the passageways 35 and 36 and establish communication between the passageway 65 35 and passageway 37. This substi-

tutes a discharge communication for the water supply communication for the end of the valve chamber in the casing so that the pressure of the water against the inner face of plunger 25 will move it to the position 70 shown in Fig. 2 as such pressure is then only opposed by the pressure in the opposite direction against the valve 26 of smaller diameter. When the discharge of the water from the air cylinder is completed through 75 the discharge connection effected by this position of the valve as above described the plunger 11 lowers until the ends of the telescoping tubes 18 engage the disk 24 through the opening in nut 23 and when the weight 80 of plunger 11 is brought to bear upon the upper ends of said tubes by the engagement of plug 16 therewith this weight serves to press the valve stem 19 downwardly to restore the position of the parts shown in 85 Fig. 1 to cause a repetition of the operation just described which becomes continuous as long as water pressure is admitted to the device.

It will be understood that the fit of the 90 valve rings 20 within the valve casing 21 is sufficiently tight to hold them in whichever position they are placed until they are positively moved by the action of the plunger 11 either to push them upwardly or to push 95 them downwardly as described.

By means of this invention a simple and effective means is provided for converting water pressure into air pressure and the device is particularly adapted for use at bars 100 or the like for supplying pressure for elevating liquids, though it is adapted for other uses.

What I claim as new and desire to secure by Letters Patent is:

An air pump, comprising an air cylinder, a weighted plunger fitting therein, telescoping tubes fitting within an opening in the plunger and provided with engaging shoulders for preventing their disengagement, a 110 tubular valve casing at the bottom of the air cylinder, a headed valve stem fitting within the telescoping tubes, a series of valve members carried by the valve stem and fitting within the valve casing with annular spaces 115 between them, there being ports through the valve casing connected by the annular spaces in the different positions of the valve stem, an annular flange on one of the valve members, a cap nut surrounding the upper end 120 of the valve casing and having a central opening through which the telescoping tubes project, but of smaller diameter than the annular flange to limit the upward movement of the valve stem, said annular flange being 125 adapted to be engaged by the telescoping tubes for moving the valve stem to its lower position when the weighted plunger is in its lower position, said valve stem being adapted to be lifted to its upper position by the 130

telescoping tubes in the upper position of the weighted plunger, and a pressure controlled valve for controlling the admission of pressure fluid to the cylinder controlled by the connections of the ports in the valve casing.

In testimony whereof, I affix my signature, in presence of two witnesses.

HERMAN E. KRUECKE.
